ATTORNEY.

UNITED STATES PATENT OFFICE.

SIDNEY O. BIGNEY, OF ATTLEBORO, MASSACHUSETTS.

BRACELET.

1,041,729.

Specification of Letters Patent.

Patented Oct. 22, 1912.

Application filed February 12, 1912. Serial No. 677,184.

To all whom it may concern:

Be it known that I, SIDNEY O. BIGNEY, a citizen of the United States, residing at Attleboro, in the county of Bristol and 5 State of Massachusetts, have invented certain new and useful Improvements in Bracelets, of which the following is a specification.

My invention relates to that class of 10 bracelets which comprises two rigid wings pivotally connected at their corresponding ends and provided with a fastening device to connect their free ends.

The essential objects of my invention are 15 to insure the wings against transverse displacement relatively to each other, to strengthen the pivotal connection, and to attain these ends by means of a structure particularly adapted to ornamentation.

20 A further object is to attain these results in a construction simple and inexpensive to construct and assemble.

To the above enumerated ends primarily, my invention consists in such parts and combinations of parts as fall within the scope 25 of the appended claims.

In the accompanying drawings which 30 form a part of this specification,—Figure 1 is a face view of my novel bracelet, Fig. 2, 35 an elevational view of the same showing in broken outline the wings of the bracelet distended, Fig. 3, a section of the bracelet taken on line *x* *x* of Fig. 2 viewed in the direction of the arrows, and Figs. 4 and 5, 45 sections of the same on lines *y* *y* and *z* *z* respectively of Fig. 2.

Like reference characters indicate like parts throughout the views.

In detail my bracelet comprises two rigid 40 curved arms or wings A and B, comprising preferably ornamental portions *a* and *b* near their corresponding connected ends and portions *a'* and *b'* at their corresponding free ends, the portions *a'* and *b'* being 45 hollow or tubular. These wings are pivotally connected as follows: A cylindrical sleeve C has integral with its lower end or soldered thereto a hemispherical or enlarged bearing portion *c*, to whose side is fixed by 50 solder as at *c'* a wing B. For the purpose of ornamentation, an ornamented plate *d* is soldered or otherwise fixed to the front portion of the sleeve C. A second member of 55 the pivotal connection comprises a tube or sleeve E having integral with one end or soldered thereto a hemispherical or enlarged

bearing portion *e* to which is soldered, as at *e'*, a wing A. An ornamental plate *f* is in the present instance soldered to the front of the sleeve E. A pin or pintle G passes 60 through the sleeves C and E. The ends of the pintle G are headed over at their upper and lower ends, as at *h* and *i* respectively, these members preventing the escape of the pintle relatively to the sleeves. If preferred, 65 one of the sleeves C or E may be rigidly connected with the pintle, in which case obviously the heading over of one of the ends *h* or *i* may be omitted.

Any catch or fastening means may be 70 employed upon the free ends of the wings. In the present instance, there is soldered or otherwise fixed in the end of the wing B, a hollow projection J projecting beyond the end of the wing and provided with an opening *j* in its exposed end. The wing A is provided with an opening *k* in its wall near the end, and has fixed by solder or otherwise within the wing, a block L, integral with or soldered to which is a spring arm 80 or latch *l* provided at its extremity with a notch *m* adapted to enter the opening *j* and engage the member J. Near the end of the latch *l* is a finger *n* which extends through the opening *k* in the wing and is adapted to 85 be pushed by the thumb nail to disengage the latch. It will be understood, however, that any convenient catch or fastening means may be employed in my structure other than that just described, and which 90 is shown in detail in Fig. 5.

It will be observed that the contacting edges of the bearing portions *c* and *e* are at a greater radial distance from the pintle G than are the corresponding sleeves C and E. 95 These extended bearing areas therefore when used in conjunction with the sleeves of less diameter insure the wings against transverse strain and displacement during use. This advantage is still further emphasized by the proportionately extended bearing surfaces afforded by the sleeves. Under usual conditions such an extended pivotal connection transversely disposed with relation to the wings might be somewhat unsightly, but the sleeves themselves afford an advantageous facility for the application thereto of ornamental plates such as *d* and *f*. 100

What I claim is,—

1. In a bracelet, the combination of a pintle, sleeves upon the pintle, enlarged bearings upon the adjacent ends of the sleeves 110

directly abutting each other, a curved wing fixed to each enlarged portion with their free ends abutting each other, and means for fastening said free ends.

5 2. In a bracelet, the combination of a pintle, sleeves upon the pintle, hemi-spherical bearings upon the adjacent ends of said sleeves provided with edges in direct slideable contact with each other, and wings fixed

to said bearings, the free ends of said wings 10 abutting each other.

In testimony whereof I have affixed my signature in presence of two witnesses.

SIDNEY O. BIGNEY.
